UNITED STATES PATENT OFFICE.

HENRY MILLER, OF PITTSBURG, PENNSYLVANIA, ASSIGNOR OF THREE-FOURTHS TO THOMAS MILLER, DANIEL H. STOEHRE, AND ALVA A. MOORE, ALL OF SAME PLACE.

DESIGN FOR A FLOWER-VASE.

SPECIFICATION forming part of Design No. 19,977, dated July 1, 1890.

Application filed June 4, 1890. Serial No. 354,297. Term of patent 3½ years.

To all whom it may concern:

Be it known that I, HENRY MILLER, a citizen of the United States, residing at Pittsburgh, in the county of Allegheny and State of Pennsylvania, have invented certain Designs for Flower-Vases; and I do hereby declare the following to be a full, clear, and exact description of the invention, reference being had to the accompanying drawing, which forms part of this specification.

My invention has relation to designs for flower-vases; and it consists of a vase mounted upon a spherical base containing an image of a group of flowers.

In the illustration accompanying this specification, A represents the upper portion of the vase, and B the base.

C C represent the flowers composing the group in the base.

Having described my invention, I claim— 20

The design for the flower-vase herein shown and described, consisting of a cup mounted upon a spherical base, said vase containing an image of a group of flowers.

In testimony that I claim the foregoing I 25 have hereunto set my hand this 7th day of March, 1890.

HENRY MILLER.
